RECEPTACLE FOR LIQUID SPRAYERS

Erwin C. Horton, Hamburg, N. Y., assignor to
Trico Products Corporation, Buffalo, N. Y.

Application April 1, 1939, Serial No. 265,617

7 Claims. (Cl. 221—85)

This invention relates to washers for the windows of vehicles, and to devices of a similar nature, and has particular relation to an improved means for mounting parts of such devices and for rendering them accessible for filling with the liquid with which they operate.

Devices of this character include a container for liquid to be sprayed or otherwise applied to a window, conduit means for carrying the liquid to or directing it against the window, and means for pumping the liquid from the container and through such conduit means. The present invention provides an improved structure for connecting and mounting the several parts, whereby the container may be easily attached or detached, and when attached will be securely held in place, and also provides an improved and efficient filler valve means, whereby the container may easily be filled and refilled with liquid.

These and other objects and advantages, including those arising from the novel structure, and arrangement of the several parts, will become apparent from the following description of the typical embodiment of the invention shown in the accompanying drawing, wherein:

Fig. 1 is a front elevation of the container, pump and supporting parts;

Fig. 2 is a plan view of the parts shown in Fig. 1, except for the pump parts which are indicated by broken lines;

Fig. 3 is an exploded perspective view showing the supporting means, filling valve, and pump parts in disassembled relation;

Fig. 4 is a fragmentary vertical sectional view through certain of the parts shown in Fig. 3, on a larger scale;

Fig. 5 is a detailed perspective view of fragments of the parts for securing the container to the supporting means; and

Fig. 6 is a detail vertical sectional view taken through the lower central part of the supporting bail shown in Fig. 1.

As shown in the drawing, the device includes a pump unit 11 having an intake and an outlet for liquid, and also having a connection to a source of variable pressure, such as the intake manifold of an internal combustion engine, which variable pressure may serve to actuate the pump.

In the illustrated embodiment the casing of pump unit 11 has a part 12 with a depending nipple 13, threaded externally for attachment to other parts. The nipple is also threaded internally for connection to the threaded end 14 of a liquid intake tube 15 through which liquid is drawn into the pump unit. Also opening into

the pump unit through part 12 is a fitting 16 connecting a conduit 17 that may extend to a suitable source of variable pressure (such as the intake manifold of a vehicle engine) not shown. An outlet conduit 18 from the pump unit may 5 carry liquid into adjacency with a vehicle windshield or the like.

The structure of the unit 11 and the connections for the conduits extending to and from it may be of the kind shown in my co-pending application Serial No. 265,616, filed on even date herewith, entitled Windshield clearing system.

Supporting means for the pump unit 11 include a plate 19 having a depending integral bracket part 21 and integral upstanding bracket 15 parts 22. Openings 23 are provided in the bracket parts for suitable fasteners by which the plate may be secured to a dash board 24 of the vehicle or to another suitable support. The nipple 13 of pump unit 11 extends through an opening 25 in 20 plate 19 and is secured by a nut 26 threaded thereto.

A cap 27 secured against the lower surface of plate 19 by suitable fasteners, such as rivets 28, receives the open upper end of a container 29. 25 The latter, preferably in the form of a glass jar, is clamped in place by means including a screw 31 and a bail 31. The latter may comprise a U-shaped piece of strap metal whose ends are notched to provide each with a narrow stem part 30 32 and shoulders 33 joined by angular parts 34. The plate 19 has its opposite sides provided with recesses 35 whose mouths are restricted by lips 36.

The stem parts 32 of the bail are narrow 35 enough to pass the lips 36 and enter into the recesses 35. Thereupon the bail may be moved downwardly relative to plate 19 to cause the latter to abut shoulders 33 and angular parts 34 to engage behind lips 36.

The screw 31 of the clamping means is screw-threaded through an opening in the central bottom portion of bail 31 where the bail is reinforced by a channel-shaped member 38, the screw also being screw-threaded through the 45 member 38, as shown in Fig. 6. A foot member 39 is swivelly connected to an end portion of screw 31, for bearing upon the bottom of container 29, and a handle 41 is formed on the other end of the screw. It will be noted that when the 50 screw 31 is tightened, tending to draw the bail downwardly relative to plate 19 and container 29, the end portions of the bail tend to move toward one another due to downward bowing of the central part of the bail. This action dissipates any 55

tendency of the upper portions of the bail to become displaced from within the recesses 35.

For filling the container without removing it from the assembly, a filler opening 42 through plate 19 and cap 27 is provided. A closure 43 for the opening 42 has an aperture 44 through which tube 15 extends, and a finger 45 projecting beyond the edge of plate 19 by which the closure may be moved pivotally about the tube. Aperture 44 is sufficiently larger in diameter than tube 15 that a spacer 46 in the form of a lock washer may be disposed within it and about the tube.

The bottom of the spacer 46 abuts the plate 19 and the top thereof abuts an annular shoulder 47 on casing part 12. Around the latter and abutting surface 48 of part 12 is a ring 49 having radially extending resilient fingers 51. A gasket 52 and washer 53 are disposed about threaded nipple 13 between cap 27 and nut 26.

Upon tightening of the latter compressing spacer 46, it will be seen that annular shoulder 47, spacer 46, plate 19 and cap 27, gasket 52, washer 53 and the nut 26 will be firmly clamped together against relative displacement. The closure 43 will be pressed against plate 19 by the resilient fingers 51, so that it will be held frictionally against accidental displacement, although it can be pivotally moved about the longitudinal axis of tube 15 to a position uncovering the filler opening 42.

In the preferred form of the invention the rivets 28 are so placed that the heads of two of them are disposed on opposite sides of closure 43, and, by extending above the surface of plate 19, require that the closure be elevated slightly before it can be swung to open position, thereby preventing the closure from being opened accidentally, or from creeping open by reason of vibration of the vehicle to which the apparatus is applied.

It will be understood that the apparatus herein shown and described is merely illustrative of the inventive principles involved, and that these principles may be otherwise embodied without departing from the principles of the invention or the scope of the appended claims.

I claim:

1. In apparatus of the class described, a supporting plate having an aperture therethrough, a pump casing having an annular shoulder and an internally and externally threaded nipple depending therefrom, a compressible spacer around said nipple and between said shoulder and plate, a member screw-threaded externally to said nipple for compressing said spacer between the plate and said annular shoulder, a container, means including a bail secured to said plate for securing the container beneath said plate, a pump inlet pipe threaded internally into said nipple and extending into said container, said plate having a filter opening therethrough for passing liquid into said container, a closure for said opening disposed upon said plate and about said spacer, and a resilient member disposed about said shoulder and flexed between the pump casing and said closure for resisting displacement of the latter.

2. In apparatus of the class described, a supporting plate, an open-mouthed container disposed beneath said plate, a cap for said container disposed against the face of said plate, a pump casing secured upon said plate and having an inlet tube extending through said plate and cap into said container, a filler opening extending through said plate and cap, a closure against the upper face of said plate movable about said inlet tube to cover or uncover said opening, resilient means between said closure and pump casing, and rivets securing said plate and cap together having heads disposed adjacent opposite sides of the closure when the latter covers said opening.

3. In apparatus of the class described, a pump casing, a supporting member therefor, said casing being clamped to said member and having a tubular part extending therethrough, said supporting member having an opening therein, a closure for the opening disposed upon the supporting member and mounted for movement about said tubular part, and a resilient member engaging between said casing and closure for resisting motion of the latter.

4. In apparatus of the class described, a container, a cap for the container, a supporting plate and fasteners securing said cap to the plate, said cap and plate having a filler opening therethrough, a closure for said opening and resilient means for holding it upon said plate, and said fasteners having heads above the surface of said plate adjacent opposite sides of said closure for holding the latter against accidental lateral displacement.

5. In apparatus of the class described, a supporting plate, a cap secured against the bottom surface of said plate, an open-topped container having its upper portion disposed in said cap, a bail of substantially U-shape having its upper portions releasably secured to said plate and its bottom portion extending beneath said container, and a member screw-threaded to said bottom portion of the bail for clamping the container against said cap.

6. In apparatus of the class described, a supporting member, a supported member, and means clamping said members together comprising a bail having end portions engaged with said supporting member and a screw threaded through said bail and engaging said supported member, said supporting member having a recess and a lip extending over the mouth of the recess, and one end of said bail being formed to pass into said recess and having portions adapted to abut the upper surface of said supporting member and to engage in said recess behind said lip.

7. In apparatus of the class described, a plate, a supported member, and a securing member for holding the supported member relative to the plate, said plate having a recess in an edge thereof and a lip extending over the mouth of the recess, and a part of said clamping member being formed to pass into said recess and having portions adapted to abut a face of the plate and to engage in said recess behind said lip.

ERWIN C. HORTON.
